APPARATUS FOR WINDING YARN

Barry Mitchell, Elizabethton, Tenn., assignor to
 North American Rayon Corporation, New York,
 N. Y., a corporation of Delaware

Application February 15, 1950, Serial No. 144,276

6 Claims. (Cl. 242—118)

1

This invention relates to apparatus for winding natural or synthetic yarn. More particularly this invention relates to a device for retaining a flexible and elastic outer covering over a rayon yarn spool or bobbin by holding the ends of the covering in the inside of the end portions of the spool or bobbin.

An object of this invention is to provide a flexible device adapted to fit into the ends of a substantially rigid cylinder adapted to be used as a yarn spool or bobbin, for holding the ends of the flexible outer covering so as to hold said covering stretched over the outside of said cylinder.

Another object of this invention is to provide a device for holding the ends of a flexible outer covering for a yarn spool or bobbin tucked into the ends of the cylinder of the spool or bobbin in such a way that the ends of the flexible covering may be manually released from the ends of the cylinder.

A further object of this invention is to provide a simple flexible member for each end of a rayon take-up spool for the purpose of holding the ends of the sock drawn over the spool when a rayon cake is being wound on the spool and for manually releasing the ends of the sock after the rayon cake is wound on the spool so that the sock may be drawn over the outside of the rayon cake to protect the cake during wet treatment.

Still another object of this invention is to provide a device consisting of a flexible disc with a plurality of radially extending fingers adapted to engage the inside of a cylindrical spool for the purpose of holding the ends of a tubular wrapper or sock for said spool on the inside of said spool during the winding of rayon thread over said wrapper and said spool.

Other and further objects of this invention will be apparent to those skilled in the art to which it relates from the following specification, claims and drawing.

In accordance with this invention there is provided a simple and convenient device that is adapted to fit in each end of the cylindrical spool or bobbin for the purpose of holding the end portions of the spool or bobbin wrapper or covering inside of the spool or bobbin during the winding of rayon yarn or thread over the wrapper and the spool or bobbin.

In the production of rayon it is often desirable to wet process the cake of yarn spun by the spool or bobbin system. During this process it is usually necessary to protect the yarn cakes by means of a fabric sock or wrapper that covers the cake completely on all sides including the

2

outside, inside and both ends. The yarn cakes which are not self supporting must be wrapped while they are still on the cylindrical spool or bobbin and this may be done by winding the yarn or thread over the sock or wrapper that is snugly fitted to the outside cylindrical surface of the spool or bobbin. The present invention provides a convenient means for holding the ends of this wrapper securely inside of the spool or bobbin in such a manner that the wrapper is stretched in a tight and wrinkle free fashion over the outside of the spool or bobbin during the winding of the yarn on the spool or bobbin. After the yarn is wound on the spool or bobbin so as to form a cake of the desired size the ends of the wrapper are manually released from the inside of the spool or bobbin and pulled over the outside of the finished cake so as to cover the ends and outside of the cake completely. The cake and wrapper are then removed from the spool or bobbin for further processing in the wet treatment.

Further details of this invention are set forth in the following specification, claims and drawing.

25 Referring to the drawing briefly:

Fig. 1 is a side view of a spool with the wrapper retaining device of this invention mounted near each end;

30 Fig. 2 is a sectional view taken along the line 2—2 of Fig. 1 showing the ends of the fingers of the wrapper retaining device extending out of the cylindrical portion of the spool;

35 Fig. 3 is a side view of the bobbin with the flexible sock or wrapper stretched over the outside cylindrical surface thereof and with the ends of the sock or wrapper tucked into the ends of the cylindrical portion of the bobbin and held therein by the fingers of the retaining devices;

40 Fig. 4 is an end view of the device shown in Fig. 3;

Fig. 5 is a view of a tool employed for the purpose of stuffing the end of a wrapper into the hollow end of the cylindrical portion of a bobbin;

45 Fig. 6 is a fragmentary sectional view showing pressure being applied manually to the center of the retaining device for the purpose of releasing the ends of the fingers thereof from the sock or wrapper;

55 Fig. 8 is a view of the wrapped rayon cake after it has been removed from the bobbin;

Fig. 9 is an end view of a bobbin with a modified form of wrapper retaining device;

Fig. 10 is a fragmentary end view of the bobbin shown in Fig. 9, the sectioned portion of Fig. 10 being taken along the line of 10—10 of Fig. 9;

Fig. 11 is a view in partial section of a modified form of retaining device applied to a substantially rigid cylinder for holding a wrapper thereon;

Fig. 12 is an end view of the device shown in Fig. 11;

Fig. 13 is a plan view of the flexible retaining member with the leaders attached to the ends of the fingers;

Fig. 14 is a view showing the fingers of the retaining device being inserted into the holes formed in the barrel portion of the bobbin;

Fig. 15 is a sectional view of the tool for inserting the fingers of the flexible retaining member into holes formed in the barrel of the bobbin;

Fig. 16 is a sectional view taken along the line 16—16 of Fig. 15;

Fig. 17 is a sectional view along the line 17—17 of Fig. 15;

Fig. 18 is a sectional view along the line 18—18 of Fig. 15;

Fig. 19 is a sectional view along the line 19—19 of Fig. 15;

Fig. 20 is a sectional view of the tool shown in Fig. 15 showing the flexible retaining member held on one end of the tool and positioned in the central hole of the bobbin with the leaders of the fingers of the flexible retaining member extending into the radial holes formed in the barrel of the bobbin;

Fig. 21 is a sectional view along the line 21—21 of Fig. 20 and

Fig. 22 is a sectional view along the line 22—22 of Fig. 20.

Referring to the drawing in detail there is shown in Figs. 1 and 2 a bobbin provided with a central barrel member 10 projecting from each end of the bobbin cylinder 11 and connected thereto in a conventional manner. The portions of the barrel member 10 projecting beyond the ends of the cylinder 11 are provided with a plurality of radially disposed holes 12 as shown in the sectional view of Fig. 2, for receiving the radiating fingers of the flexible retaining device 13 which is made of sheet rubber or similar material of the desired resilience including flexible sheet metal. Two of these flexible retaining members are provided for each bobbin as shown in Fig. 1 and each member is made with a ring-shaped central portion which is provided with a hole of suitable diameter to fit on the end of a peg designed for holding the entire bobbin during transportation. Radiating from the ring-shaped member are the fingers 14 each of which is provided with portions 15 that are relatively wider than the diameter of the holes 12. Narrower portions 16 of the fingers 14 connect the wider portions 15 to the central ring member and these narrower portions 16 are substantially smaller than the diameters of the holes 12 so that these portions fit loosely into these holes. The narrower portions 16 are normally lodged in the holes 12.

The flexible retaining member 13 is made of an overall diameter slightly greater than the diameter of the outside of the cylinder 11 as shown in Fig. 2 so that the ends of the retaining member fingers 14 apply slight pressure to the inside of the cylinder 11 when the end of these fingers 14 are pressed into the inside of the

cylinder 11 for the purpose of holding the sock or wrapper 17 stretched over the outside of this cylinder as shown in Figs. 3 and 4.

When the sock or wrapper 17 is to be stretched over the outside of the cylinder 11 it is first drawn over the outside of the cylinder and assumes a more or less ruffled or irregular shape as shown in Fig. 5. At the same time the ends of the fingers 14 may be resting either on the edges of the ends of the cylinder 11 or they may be pressed into the inside of the cylinder into engagement with inner surfaces of the cylinder. With the bobbin standing up on one of its ends as shown in Fig. 5, one end of the sock or wrapper 17 is gathered around the top edge of the cylinder 11 ready to be pressed into the inside of the cylinder by means of the stuffing tool 18 which consists of a cup-shaped body member having an outside diameter somewhat smaller than the inside diameter of the cylinder 11 and also having a handle 19. With the top of the tubular wrapper or sock 17 gathered up over the inside top edge of the cylinder 11, the operator takes the stuffing tool 18 by the handle 19 and brings the lip of the cup-shaped member down over the collected end of the tubular wrapper or sock 17 and forces the lip of this tool and the gathered wrapper or sock into the inside of the cylinder 11. Since the fingers 14 of the retaining device 13 are of flexible material they are bent inward into the cylinder 11 and permit the fabric of the wrapper 17 to be pressed into the cylinder. However, the fingers 14 of the retaining member 13 are made of sufficient strength so that when the stuffing tool 18 is withdrawn from the cylinder the ends of the fingers 14 press the fabric of the wrapper 17 against the inside of the cylinder 11. Both ends of the tubular wrapper or sock 17 are stuffed into the cylinder 11 using the tool 18. Furthermore, because the holes 12 through which the fingers 14 of the retaining member 13 are threaded, are positioned just outside of the inside of the cylinder 11, the fingers 14 assume an arched configuration applying pressure in a direction such that these fingers tend to maintain the wrapper 17 in stretched form over the outside of the cylinder 11 as shown in Fig. 3. This is especially true when both ends of the wrapper or sock 17 are stuffed into the cylinder 11.

After the rayon yarn is wound on the stretched wrapper 17 of the bobbin to form a cake of the desired size, the ends of the fingers 14 may be caused to disengage the wrapper inside of the cylinder 11 by manually pressing the center of the retaining device 13 as shown in Fig. 6. The ends of the wrapper 17 may then be withdrawn from the inside of the cylinder 11 without difficulty and the end portions of the wrapper 17 are then pulled over the outside of the rayon yarn to completely cover the yarn as shown in Fig. 7. The completely wrapped rayon cake is then removed from the cylinder 11 because this cylinder is slightly tapered from one end to the other and the cake then collapses into a shape such as shown in Fig. 8.

Modified forms of the flexible retaining device of this invention are shown in Figs. 9, 10, 12 and 13. The modification shown in Figs. 9 and 10 consists of a flexible retaining member 20 having a ring-shaped body portion provided with a hole of such size that the flexible retaining member may be stretched over the end of the bobbin barrel 21 to be lodged in the groove 22 that is cut into the outside of this barrel substantially in line with the end of the slightly tapered

cylinder 23 of the bobbin. When the ends of the tubular wrapper or sock 24 are pressed into the inside of the cylinder 23 with the stuffing tool 18 shown in Fig. 5 the relatively blunt fingers 25 grip the fabric of the wrapper 24 against inside surfaces of the cylinder 23 and hold the wrapper 24 stretched over the outside of the end of the cylinder 23. For this purpose the overall diameter of the retaining device 20 is made somewhat greater than the inside diameter of the cylinder 23 so that the retaining device 20 becomes slightly arched or curved when the end of the tubular wrapper is stuffed past the retaining device into the inside of the cylinder and the retaining device fingers are released by the stuffing device to grip the wrapper. When it is desired to release the ends of the wrapper held by the modified retaining device shown in Figs. 9 and 10, that is, when rayon yarn has been wound on the wrapped cylinder, and it is desired to cover the outside of the yarn with the end portions of the wrapper, the operator must bend the retaining device 20 out of the inside of the cylinder 23. For this purpose the operator simply sticks his fingers into the openings provided between the retaining device fingers 25 and bends the flexible retaining device outward.

The modified form of this retaining device shown in Figs. 11 and 12 consists of a flexible member 30 positioned in each end of the cylinder 31 to hold the wrapper 32 stretched over the outside of the cylinder. In this case the retaining devices 30 are each provided with a relatively large body member with radially extending short and blunt fingers 33. The overall diameter of the retaining device 30 including the fingers 33 is made somewhat greater than the outside diameter of the cylinder 31 so that when the retaining device 30 is inserted into the end of the wrapped cylinder both the body and the fingers of this retaining device assume a bowed configuration as shown in Fig. 11, for the purpose of exerting slight pressure against the inside of the cylinder 31. This bowed configuration is such as to oppose the withdrawal of the wrapper from the inside of the cylinder. Furthermore this same configuration is useful for stretching the wrapper 32 over the outside of the cylinder 31. When it is desired to pull the ends of the wrapper from the inside of the cylinder the operator may remove the retaining device 30 by inserting a finger in the hole 34 of the device and withdrawing the device from the cylinder.

In Fig. 13 there is illustrated a plan view of the retaining device 13 such as is employed in the bobbin shown in Figs. 1, 2, 3, 4, 6 and 7. This retaining device 13 is provided with leaders 14a attached to the ends of the fingers 14 to facilitate inserting these fingers into the holes 12 formed in the barrel 10 of the bobbin. One method of inserting these fingers 14 into the holes 12 is illustrated in Fig. 14 in which the retaining device 13 is folded and the fingers 14 are partially inserted into the axial hole of the barrel so that the leaders 14a extend across the inside openings of the holes 12. Thereafter a hook 12a is inserted into one of the holes 12 from the outside and the corresponding leader 14a is caught by the hook 12a and pulled through the hole 12. For this purpose the leaders 14a are made of relatively small cross section so that they may be easily pulled through these holes. After all of the leaders 14a are pulled through the holes 12 the operator grips these leaders individually and pulls the fingers 14 until the narrow

portions thereof are lodged in the holes as shown in Fig. 2. He then takes a pair of shears and removes the leaders 14a from the fingers 14.

In Fig. 15 there is shown a tool that facilitates the placing of the retaining devices shown in Figs. 1, 2, 3, 4, 6 and 7, into the holes 12 provided therefore as previously described. The advantage of this tool is that it saves a great deal of time in inserting these retaining devices. This tool is provided with a slotted or grooved cylinder 40 that fits into the axial hole of the bobbin barrel 10. A plurality of slots or grooves 41 corresponding to the holes 12 formed in the barrel 10 are cut into this cylinder 40 and these slots or grooves are open through approximately half the length of the cylinder 40, the inside ends of these slots terminating in arcuate guide surfaces 42 that are carried by the fillers 43 and the purpose of which will be explained in greater detail in connection with Fig. 20. The fillers 43 are formed integral with the flange 56 and this structure is keyed to the cylinder 40 by pins 44. A handle 45 is attached to one end of the cylinder 40. A slotted tubular member 46 of substantially smaller diameter than the aforesaid cylinder 40 is positioned inside of the cylinder 40 and is axially moveable with respect to the latter. An inwardly extending flange 47 is provided at one end of the cylinder 40 to function as a bearing for the tubular member 46. Slots 48 are cut into the tubular member 46 and these slots extend longitudinally throughout a substantial length of the tubular member 46 to permit expansion of the slotted part of this member 46 particularly the head portion 49 which is provided with a groove 50 that is adapted to be expanded into and engage the central hole of the flexible retaining device 13 as shown in Fig. 20. After the flexible retaining device 13 is placed on the head 49 the expander cone 51 is drawn into the head 49 of the slotted tubular member 46 by the rod 52 and the small handle 53 attached thereto by the pin 54. A portion of the handle 53 is positioned in a slot formed in the rod 52 and after this rod 52 is drawn into the slotted tubular member 46 until the expander 51 is inserted on the head 49 as shown in Fig. 20 the end 55 of the handle and latch device 53 is released from the tubular member 46 and latches on the end of the latter member as shown in Fig. 20. In this way the head 49 is held expanded and holds the flexible retaining device 13 positioned thereon. The tool with the flexible retaining device 13 positioned thereon is now ready to be inserted into the axial hole of the barrel 10 and for this purpose the fingers 14 of the flexible retaining device 13 must be folded over and into the slots 41 of the cylinder 40. When the tool and the expanded flexible retaining device 13 are inserted into the axial hole of the barrel 10 until the flange 56 that is attached to the handle end of the cylinder 40 abuts the end of the barrel 10, the tool is in position to guide the leaders 14a of the fingers 14 of the flexible retaining device 13 into the holes 12 formed in the barrel 10. This is done when the operator grips the handles 45 and 57, the hand portions of which are rounded as shown in Fig. 22, and pulls the hand portion of the handle 57 towards the hand portion of the handle 45. The handle 57 is slidably attached to the handle 45 by the rivets 58 which are fixed to the handle 57 and slide in the slots 59 cut into the sides of the handle 45. The handle 57 is attached to the tubular member 46 and moves this tubular mem-

ber 46 with respect to the cylinder 40 thereby forcing the fingers 14 and the leaders 14a to move in the slots 41 of the cylinder 40 so that the leaders 14a are guided by the curved slide surfaces 42 into the holes 12 of the barrel 10. For this purpose these curved slide surfaces 42 are made to lead these slots 41 toward the holes 12 as shown in Fig. 20. The leaders 14a are thus guided into the holes 12. The fingers 14 are guided into these holes by the leaders 14a when the tool is pulled out of the axial hole of the barrel 10. When the tool is pulled out so that the head 49 is opposite the holes 12 the latch 55 of the handle 53 may be released to permit the head 49 to contract and release the flexible retaining device 13 since this device is now in the desired position. The leaders 14a then may be cut off from the fingers 14 and the flexible retaining device 13 is ready for use to retain the wrapper or sock stretched over the cylinder 11.

This invention is susceptible of various modifications and it is not desired to limit the invention to the exact details shown and described except in so far as those details may be set forth in the claims. Although the invention has been specifically described in connection with the winding of rayon yarn, it is, of course, to be understood that any other cellulosic or non-cellulosic yarn may be wound in accordance with this invention.

What I claim is:

1. A covered bobbin for winding yarn or the like comprising a substantially rigid cylindrical member, a co-axial member positioned in said cylindrical member and projecting out beyond the ends of said cylindrical member, said co-axial member being hollow and being adapted to be positioned on a rotatable shaft, a flexible covering for the outside of said cylindrical member, the ends of said flexible covering being tucked into the hollow ends of said cylindrical member, and a flexible retaining device supported in holes formed in the ends of said co-axial member, said flexible retaining device having fingers projecting out of said holes, said fingers of said flexible retaining device being adapted to press surfaces of said flexible covering against inside surfaces of said cylindrical member to hold said flexible covering stretched over the outside of said cylindrical member.

2. A covered bobbin for winding yarn or the like comprising a substantially rigid cylindrical member, a co-axial member positioned in said cylindrical member, a flexible covering for the outside of said cylindrical member, the ends of said flexible covering being tucked into the hollow ends of said cylindrical member, and a flexible retaining device supported in holes formed in the ends of said co-axial member, said flexible retaining device having fingers the ends of which are adapted to press surfaces of said flexible covering against inside surfaces of said cylindrical member to hold said flexible covering stretched over the outside of said cylindrical member.

3. A covered bobbin for winding yarn or the like comprising a substantially rigid cylindrical member, a co-axial member positioned in said cylindrical member and projecting out beyond the ends of said cylindrical member, a flexible covering for the outside of said cylindrical member, the ends of said flexible covering being tucked into the hollow ends of said cylindrical member, and a flexible retaining device having radially disposed fingers supported in radially

extending holes formed in the ends of said co-axial member projecting out of said cylindrical member, the ends of said fingers being adapted to press surfaces of said flexible covering against inside surfaces of said cylindrical member to hold said flexible covering stretched over the outside of said cylindrical member.

4. A device for winding yarn comprising a substantially rigid cylindrical bobbin having hollow ends, a flexible covering for the outside cylindrical surface of said bobbin, a pair of flexible retaining devices, one for each end of said bobbin, means for holding said flexible retaining devices in the correspondings ends of said bobbin, each of said flexible retaining devices having fingers around the periphery thereof, said fingers being sufficiently flexible and of sufficient length so that they may be temporarily pushed aside while said retaining devices are held by said means to permit stuffing of the ends of said covering into the hollow ends of said bobbin and to thereafter spring against said covering stuffed into said bobbin to dig into and grip said covering to hold said covering stretched over said cylindrical surface substantially free of wrinkles.

5. A device for winding yarn comprising a substantially rigid cylindrical bobbin having hollow ends, a flexible covering for the outside cylindrical surface of said bobbin, a pair of flexible retaining devices, one of said devices for each end of said bobbin, means connected to said bobbin for supporting said flexible retaining devices in correspondings ends of said bobbin, said flexible retaining device having the peripheral portions thereof of sufficient flexibility so that they may be temporarily pushed aside while said retaining devices are supported by said means to permit the stuffing of the ends of said covering into the hollow ends of said bobbin and to thereafter spring against said covering stuffed into said bobbin to dig into and grip said covering to hold said covering stretched over said cylindrical surface substantially free of wrinkles.

6. A device for winding yarn comprising a substantially rigid cylindrical bobbin having hollow ends, a flexible covering for the outside cylindrical surface of said bobbin, a pair of flexible retaining devices, one of said devices positioned in each end of said bobbin, means for holding said flexible retaining devices in the correspondings ends of said bobbin, each of said retaining devices comprising a member positioned substantially at right angles to the axis of said bobbin, the peripheral portions of said member being highly resilient and extending from said member to engage the portion of said flexible covering tucked into the hollow ends of said bobbin and to press said portions of said flexible covering against inside surfaces of said bobbin, said peripheral portions being bent inward into the hollow ends of said bobbin so that the free edges thereof dig into said flexible covering contacted thereby and so that increased tension of said flexible covering extending over the outside of said bobbin increases the firmness of the aforesaid contact of said peripheral portions with said flexible covering.
